UNITED STATES PATENT OFFICE.

ADOLPH LIETZ, OF SAN RAFAEL, CALIFORNIA.

COMPENSATING BINNACLE.

1,241,132.

Specification of Letters Patent. Patented Sept. 25, 1917.

Application filed May 15, 1916. Serial No. 98,995.

To all whom it may concern:

Be it known that I, ADOLPH LIETZ, a citizen of the United States, residing at San Rafael, in the county of Marin and State of California, have invented a new and useful Improvement in Compensating Binnacles, of which the following is a specification.

My invention relates to compensating mechanism for binnacles and the like whereby in the position of permanent magnets is adjusted to correct deviations of the compass caused by magnetism induced within the hull of a ship.

The hull of an iron or steel ship is a magnet and the distribution of its magnetism depends upon the direction of the ship's head when building, this result being produced by induction from the earth's magnetism, developed and impressed by the hammering of the plates and frames during the process of building.

The disturbance of the compass by the magnetism of the hull is generally modified, sometimes favorably, more often unfavorably, by the magnetized fitting of the ship, such as the masts, deck houses, engines and boilers. For this reason the compass needle in every ship is more or less subject to various deviations among which may be mentioned, first, horizontal forces acting in a longitudinal direction in the ship and caused partly by the permanent magnetism of hard iron or steel which is generally corrected or compensated by permanent magnets horizontally placed in a fore and aft direction and partly by vertical induction in vertical soft iron either before or abaft the compass; and second, forces acting in a transverse direction, and caused by hard iron, which deviation is compensated by means of permanent magnets athwartships and horizontal.

There are several other deviations due to other causes but these will not be enumerated as they have no part in the present invention which is to provide a means whereby the fore and aft magnets, provided for the first mentioned deviation, and the athwartships or beam magnets provided for compensating the second mentioned deviation, may be easily and quickly adjusted to correctly compensate the deviations mentioned, under various conditions.

I accomplish these features by means of the device disclosed in the drawings forming a part of the present specification wherein like characters are used to designate simi-

lar parts throughout the said specification and drawings and in which—

Figure 1 is a front elevation of a binnacle with the housing door removed disclosing the arrangement and location of the permanent magnets and the trays provided for their support.

Fig. 2 is an enlarged plan view of the trays and supporting mechanism therefor removed from the housing of the binnacle, and

Fig. 3 is a plan view of Fig. 2 of the drawings.

Referring to the drawings, the numeral 1 is used to designate the body or housing of a binnacle having a vertically disposed hollow tube 2 which if projected, would penetrate the center of the compass above, and is provided with a rack 3.

A tray 4, having a bearing sleeve 6 slotted to receive the rack 3, is slidably mounted upon the tube 2 and is provided with opposite apertured webs 7 adapted to retain the permanent fore and aft magnets 8 on each side of the vertical center of the binnacle. The sleeve 6 is provided with lugs 9 within which is rotatably mounted a suitable pinion 11 meshing with the rack 3 and having an extended stem 12 provided with a squared end adapted to receive and be rotated by a suitable wing nut 14.

The split sleeve 6 is also provided with a second set of lugs 16 adapted to be drawn together and thereby tightly engage the tube 2, so as to rigidly secure the tray 4, by means of a threaded stem 17 having a squared end 18 arranged to receive and be rotated by the wing nut 14 which is detachably secured on the end of the stem 12.

A second or beam tray 18 is also provided with apertured webs 19 arranged to hold a series of permanent beam magnets 20 at right angles or transversely to the first mentioned magnets 8 and equally on both sides of a center line drawn through said magnets 8 and transversely thereto.

The beam tray 18 is slidably mounted upon a second tube 22 by means of a split sleeve 21 provided with lugs 23 within which is rotatably mounted a pinion 24 meshing with a rack 25 upon the tube 22 said pinion being secured to a shaft or stem 27 squared on the end to receive a wing nut 28 whereby said stem 27 and pinion 24 thereon may be rotated and thereby cause the tray 18 to be raised or lowered.

The split sleeve 21 is also provided with a second set of lugs 29 adapted to be drawn tightly together by means of a threaded stem 31 and thereby cause said split sleeve 21 to tightly engage the tube 22 and retain the tray 18 at the desired elevation.

The stem 31 is also squared as at 32 to receive and be rotated by the wing nut 28 which is detachably mounted upon the stem 10 or shaft 27.

The corrective or compensating positions for the permanent fore and aft magnets 8 and the beam magnets 19 lie respectively somewhere in a vertical plane coincident with the longitudinal center of the ship on which the mechanical center of the binnacle and compass therein, are placed; and in a vertical plane at right angles to and abaft the binnacle with the permanent magnets 19 placed so as the first mentioned plane will bisect them.

For convenience, the fore and aft magnets 8 are equally distributed on both sides of the longitudinal center of the binnacle 1 and 25 compass therein.

The longitudinal and transverse variations are determined separately by means of mathematical analysis and each corrected mechanically by raising or lowering the 30 trays 4 and 18.

Either tray may be raised or lowered independently of the other by first loosening the securing lugs which cause the split sleeve to tightly engage the tube on which 35 it is mounted and then rotating the pinion 11 or 24, as the case may be, until the tray and permanent magnets therein are adjusted to the proper position for correcting the deviation when the wing nut is removed 40 from the stem or shaft of the pinion operated and applied to the stem of the securing lugs for the purpose of locking the sleeve and tray securely in position.

From the foregoing it is obvious that I 45 have provided improved means for adjusting the position of corrective or compensating magnets and also improved means

whereby said adjustment may be easily and quickly secured.

Having thus described my invention what 50 I claim as new and desire to secure by Letters Patent is—

1. The combination with a binnacle and compass therein of parallel vertically disposed tubes; a magnet tray slidably mounted 55 upon each tube; means operatively connected to each tube and the tray thereon adapted to elevate either tray independently of the other; and means secured to each tray and adapted to secure the position thereof. 60

2. The combination with a binnacle and compass therein of a central vertically disposed tube having a rack thereon; a second vertically disposed tube having a rack thereon; a magnet tray slidably mounted 65 upon each tube; a pinion rotatably mounted upon each tray and meshing with the rack on the tube; means operatively connected to each pinion whereby the same may be operated to raise or lower the tray on which 70 it is mounted; and means secured to each tray and adapted to secure the same against movement on its respective tube.

3. The combination with a binnacle and compass therein of a vertically disposed central tube having a rack thereon; a second vertically disposed tube adjacent to and parallel with the first mentioned tube and having a rack thereon; a magnet tray having a split sleeve slidably mounted upon 80 each tube; a pinion rotatably mounted upon each tray and meshing with the rack on each tube; means operatively connected to each pinion whereby the same may be operated and thereby raise or lower the tray on 85 which it is mounted; and means secured to each split sleeve and adapted to open or close the same and thereby release the said sleeve from or secure the same to the tube on which it is mounted. 90

In witness whereof I hereunto set my signature.

ADOLPH LIETZ.
